PRESSING MACHINE

Pasquale Marcellitti, Elmwood Park, Ill., assignor
of one-half to Felix George, Elmwood Park, Ill.

Application April 25, 1935, Serial No. 18,151

5 Claims. (Cl. 68—9)

This invention relates to certain novel improvements in pressing machines and has for its principal object the provision of an improved construction of this character which will be highly efficient in use and economical in manufacture.

In the art of pressing garments, particularly men's coats, it is the customary practice to place upon the buck the edge portion of the coat to be pressed while suspending the remaining portion from the buck and thereafter after the edge portion of the coat has been pressed, the coat is reversed and the opposite edge portion of the coat is then placed upon the buck for the pressing operation. This method requires that the operator reverse the coat for the purposes herein stated and consequently consumes labor and time.

One of the many objects of my invention is to provide a pressing machine wherein the portions of the coat may be pressed simultaneously without requiring the reversal operation hereinbefore indicated.

Other objects will appear hereinafter.

The invention consists in the novel combination and arrangement of parts to be hereinafter described and claimed.

The invention will be best understood by reference to the accompanying drawing, showing the preferred form of construction and in which:

Fig. 1 is a fragmentary end view of a pressing machine embodying my invention;

Fig. 2 is a top plan view of the pressing buck embodied in my invention; and

Fig. 3 is a fragmentary sectional detail view of the same taken substantially on line 3—3 of Fig. 2.

Referring more particularly to the drawing, in which the preferred form of construction of my invention is illustrated, a pressing machine is indicated generally at 10 and this machine includes the usual supporting standards 11. Upon these standards is supported the present buck 12 which may be constructed of any suitable material which will best serve the purpose.

The standards 11 preferably provide a supporting lug 13 which pivotally supports a rocker arm 14 manually operated through the medium of an operating link 15 in a manner well known in the art.

50 The rocker arm 14 supports a pressing head 16 adapted to be brought down upon the buck 12 during the pressing operation.

The pressing head 16 is of a construction well known in the art including the conduits 17 for the admission of steam or the like to the interior

thereof. Likewise the pressing buck 12 is provided with means in the form of conduits for the admission of air under pressure to the interior thereof for reasons well known in the art.

The pressing buck 12 is provided with an elongated coat receiving slot or recess 18, one end of which terminates in a transversely extending slot or recess 19 which for convenience I prefer to term the coat collar receiving recess.

As shown in the drawing the opposite ends 19' of the coat collar recess or slot 19 extend beyond the longitudinal edges 21 of the coat receiving recess 18. The purpose of this construction is to permit the collar to be conveniently disposed in this recess or slot 19 without wrinkling or buckling the edge portions 22 of the coat disposed upon the buck 12 for the pressing operation.

In use, to press a coat, the major medial portion of the same is disposed through the slot 20 or recess 18 with the neck or collar portion 21 of the coat confined in the recess or slot 19. In this position of the coat the edge portions 20 are mounted upon the buck 12 in position for the pressing operation by the cooperation of the buck 12 and the pressing head 16.

This construction of the buck permits the operator to press the edge portions of the coat simultaneously and, if desired, both ends of the slot or recess 18 may terminate in coat collar receiving recesses for obvious purposes.

To facilitate supporting the coat with the edge portions 22 in pressing position upon the buck 12 I preferably mount beneath the buck a supporting shelf 25 supported from the standards 11 by 35 any suitable means, such for example, lugs 26. This supporting shelf will receive the weight of the coat and thereby serve to prevent the same from sagging through the slots by virtue of its own weight.

While I have illustrated and described the preferred form of construction for carrying my invention into effect, this is capable of variation and modification, without departing from the spirit of the invention. I, therefore, do not wish to be limited to the precise details of construction set forth, but desire to avail myself of such variations and modifications as come within the scope of the appended claims.

Having thus described my invention what I claim as new and desire to protect by Letters Patent is:

1. A pressing machine comprising a pressing head, and a pressing buck, the said buck being

provided with a coat receiving slot with the slot terminating in a collar receiving recess.

- 5 2. A pressing machine comprising a pressing head, and a pressing buck with the said buck provided with intercommunicating slots or recesses for the reception of portions of a garment while other portions of the garment are disposed in pressing relation with respect to the head and buck.
- 10 3. A pressing machine comprising a pressing head, and a pressing buck, the said buck being provided with a coat receiving slot with the slot terminating in a collar receiving recess; and a supporting shelf for a coat which may be projected through said slot.
- 15 4. A pressing machine comprising a pressing head, and a pressing buck with the said buck

provided with intercommunicating slots or recesses for the reception of portions of a garment while other portions of the garment are disposed in pressing relation with respect to the head and buck; and a supporting shelf beneath said slots for receiving the weight of said garment.

5 10 5. A pressing machine comprising a supporting frame, a pressing head pivotally supported by the frame, a pressing buck supported by the frame in pressing relation with respect to the head and having a slot or recess formed therein for the passage of portions of a garment while other portions of the garment are disposed in pressing position upon the buck on opposite sides of said slot.

15 PASQUALE MARCELLITTI.
